UNITED STATES PATENT OFFICE

2,613,098

SPINDLE AND HANDLE CONNECTION

Gunther K. E. Kleeberg, Belfast, Maine

Original application October 9, 1946, Serial No. 702,182, now Patent No. 2,510,746, dated June 6, 1950. Divided and this application May 9, 1950, Serial No. 160,954

5 Claims. (Cl. 292—355)

1

My present invention relates to door latches and particularly to the connection between latch spindles and the knobs attached thereto and this application is a divisional of my co-pending application Serial Number 702,182, filed October 9, 1946, now Patent Number 2,510,746, issued June 6, 1950.

In latches of the type with which this invention is concerned, the rotatable bolt spindles extend through rose plates and usually have knobs attached to both of their ends.

In accordance with my invention, I provide means to frictionally interlock each knob or handle to its spindle by means which so vary the relation between the peripheral extent of the spindle receiving bore in the handle and that of the spindle that the handle is suitably secured thereto.

This result may be accomplished, for example, by utilizing tubular stock and providing each extremity of the spindle with a slot and a substantially opposite and outwardly disposed rib. The hub of each handle has a groove to receive a rib and has an internal annular recess. By this construction, the handle may be keyed to the spindle and, in addition, I employ a screw extending through the hub, the hub recess and the slot. To the screw I thread a wedge-shaped nut adapted to expand the spindle against the hub to prevent the handle from being pulled from the spindle. This construction also has the advantage that the screw may be tightened until the spindle stock is deformed into the recess of the hub making the interlock between the handle and the spindle more positive even if the nut should become loose or the screw should fall out.

In accordance with my invention I am thus able to provide a door latch that is inexpensive to manufacture, simple to install, and combines ease with reliability of operation.

In the accompanying drawings, I have shown an illustrative embodiment of my invention from which these and other of its novel features and advantages will be readily apparent.

In the drawings:

Fig. 1 is a section through an installed door latch illustrating the attachment of the knobs to the spindle in accordance with my invention, and

Fig. 2 is a section along the lines 2—2 of Fig. 1.

In the drawings, I have illustrated my invention in connection with the door latch disclosed and described in my co-pending application Serial Number 702,182, filed October 9, 1946. The latch includes a housing 14 slidably supporting

2

the bolt 15. The bolt 15 is yieldably urged into its outer locking position by means of the spring 21 and is retracted into its unlocked position by rotation of the spindle 37 which is operatively connected thereto and which is rotatably supported by rose plates 35 attached to opposite sides of the door 10 and including hubs 36.

The spindle 37 is of tubular stock and at 39 I have indicated handles or knobs. In order that the handles may be attached to the extremities of the spindle 37, each of their hubs is formed with a passage freely receiving a spindle extremity in order that the peripheral extent of one of the mated parts may be varied to establish a tight frictional interlock therebetween.

Such a result may be readily attained, where at least the extremities of the spindle are tubular, by providing each extremity with a slot 40 and an external rib 41 located diametrically opposite thereto. Each hub 42 of a handle 39 has an internal annular recess 43 and a groove 44 intersecting it and establishing a keyway for a rib 41 so that the handle 39 may be effectively keyed to the spindle 37. The handle 39 may be conveniently locked to the spindle 37 to prevent its being pulled therefrom by means of a screw 45 extending through the handle hub 42, its recess 43, and a slot 40, and threaded thereon is a nut 46, preferably wedge-shaped. By this construction, the desired frictional interlock between the handle 39 and the spindle 37 is readily established by the screw 45 to expand the spindle extremity tightly against the spindle receiving bore in the hub 42. If desired, a positive interlock may be established by tightening the screw 45 until the spindle hub is deformed into the recess 43 so that even if the screw 45 became loosened or fell out, the handle could not be accidentally pulled from the spindle.

From the foregoing, it will be apparent that my invention makes possible an easily established and secure interlock between door knobs and the like and their spindles.

What I therefore claim and desire to secure by Letters Patent is:

1. In combination, a spindle member and a handle including a hub member having an aperture to receive one extremity of said spindle member, one of said members having a recess, and means to deform a portion of the other member into said recess to positively interconnect said handle and said spindle.

2. In combination, a spindle member and a handle including a hub member having an aperture to receive one extremity of said spindle

member, said hub member having an internal recess, and means to deform a portion of said spindle member into said recess to positively interconnect said spindle and said handle.

3. A tubular spindle for a door latch or the like, said spindle having at least one of its ends provided with a slot and an externally disposed rib, a handle including a hub having a groove to receive said rib and an internal annular recess and a screw extending through said hub, said 10 recess and said slot, a wedge element threaded on said screw and adapted to expand the spindle stock against the interior surfaces of said hub and to deform the stock into said recess thereby to prevent the handle from being accidentally 15 pulled from said spindle.

4. The spindle of claim 3 in which the rib is located diametrically opposite the slot.

5. A tubular spindle for a door latch or the like, said spindle having at least one of its ends 20

provided with a slot, a handle including a hub having an internal recess, a screw extending through said hub, said recess and said slot, a wedge member threaded on the end of said screw operable to expand the spindle against the interior surfaces of said hub and to deform the spindle stock into said recess to interlock said handle and spindle against accidental disengagement independently of said screw.
